land

Application April 26, 1932, Serial No. 607,640
In Germany May 4, 1931

2 Claims. (Cl. 234—36.5)

Various kinds of apparatus are in existence, in which the power, current intensity or voltage of an electrical circuit at each instant is transmitted to and recorded on a moving band or similar recording device, which is forwarded by means of a clockwork mechanism at a predetermined rate, so that a continuous diagram is obtained, which records the power or voltage of the circuit during a given period. The kinds of apparatus which 5 have been on the market hitherto (e. g. recording watt-meters) are, however, very complicated, and, above all, the cost of production thereof is so high that they are employed for the most part only in electrical works or in very large industrial 10 installations.

The present invention, however, relates to an apparatus for electrically recording only the periods of operation of an electrical power or lighting installation, the value of the power or voltage 15 at any instant not being taken into account. The diagram which will be obtained with this apparatus is intended only to show whether and over what intervals of time the installation in question 20 has been in operation or has had current supplied to it.

The means for operating the recording medium or sheet on which the diagram is to be described, which may consist either of an endless strip passing over rollers (band recorder) or of a dial (disc 25 recorder), are known per se.

In the improved apparatus the stylus which is adapted to cooperate with the recording sheet is controlled by a simple electro-magnet by means of a lever mechanism, in such a manner that the 30 stylus moves radially out of its normal or rest position when the electro-magnet is energized, so that the alteration in the path of the stylus along the sheet is recorded on the latter even if it is only temporary. As the movable member of the 35 electro-magnet remains in one position so long as current is supplied to the apparatus under observation, the period of operation thereof may be readily ascertained from the recording sheet, which is moved by the clockwork mechanism and is divided into intervals representing 40 intervals of time.

The electro-magnet will only bring the stylus 45 out of its normal position or permit it to return thereto, according to whether the circuit is closed through it at the commencement of a period of 50 operation or interrupted at the end of a period of operation, and this in such a manner, that the stylus is moved in a substantially radial direction outwards towards the edge of the sheet or inwards 55 towards the centre thereof in order to indicate

on the sheet, by these radial displacements, the commencement or end of a period of operation within the curve or diagram traced on the recording sheet.

In order that the invention may be readily understood, two constructional embodiments of an electrical recording apparatus for recording periods of operation constructed in accordance with the invention will now be described with reference to the accompanying drawings, in which

Figure 1 is a view of one construction, in part a sectional elevation thereof,

Figure 2 being a plan view thereof partly in section with the covering of the casing removed.

Figure 3 shows a second form in open position 70 of the casing.

Referring now to Figures 1 and 2, *a* is an electro-magnet which is rigidly mounted in the casing of the apparatus, *b* is a loosely mounted supporting arm for a stylus *c*, adapted to cooperate 75 with a recording sheet *m*, a support member *r* being provided for the latter.

A lever *d*, which is subject to the action of a tension spring *f* is rotatably mounted together with the supporting arm *b* of the stylus on a pin 80 *g*, the free end of the lever *d* being connected to the armature *h* of the electro-magnet *a* in such a manner that, when the armature *h* is attracted, the lever *d* is rotated about the pin *g* against the action of the spring *f*, thereby 85 rotating the supporting arm *b* so that the stylus *c* is moved radially outwards with respect to the recording sheet *m*.

In order that a blank recording sheet may be readily inserted, the stylus supporting arm *b* is formed of two distinct parts, 90 one of which is connected to the lever *d*, whilst the other is pivotally mounted on a horizontal pin *p* carried by said first arm part to allow a tilting up of the stylus carrying arm part. Clock- 95 work mechanism *i* is connected by a friction gearing (not shown in the drawings) with the keyed shaft *k* and causes the latter to rotate together with the recording sheet *m* placed thereon in the direction of the arrow *a*.

The keyed shaft *k*, and therefore the recording sheet *m* is 100 connected with the clockwork mechanism *i* through a friction gearing, in order that the diagram sheet *m* may easily be adjusted with respect to a time notch *n* provided in the support member *r*, to a determined initial time.

This apparatus is connected to a subsidiary electrical circuit which is connected to the electrical installation under observation, in such a manner that, in order to set the latter into operation the circuit leading to the coil of the

electro-magnet *a* is closed. When this occurs the armature *h* of the electro-magnet *a* is attracted, and, through the intermediary of the lever *d*, effects a corresponding deflection of the supporting arm *b* of the stylus *c*, which will commence to trace on the sheet *m* a line such as *s*, having inner and outer curved parts interconnected by radial straight lines.

As soon as the circuit is broken, the electro-magnet *a* becomes deenergized again, so that the tension spring *f* returns the lever *d*, and therefore the stylus *c*, to the initial or rest position. As shown in the drawings, a spring *o* may also be provided, if desired in the electro-magnet *a* itself, for supplementing the action of the spring *f* in effecting the return movement of the lever *d*.

The apparatus may be closed while in use by means of a safety lock, in order to prevent removal or exchange of the recording sheets by unauthorized persons. The clockwork mechanism may also be so arranged that one rotation of the sheet is performed over any desired interval of time, e. g. 24 hours, 12 hours or less, according to whether small or large intervals on the recording sheet are to represent predetermined intervals of time.

As will be evident from the foregoing description, the stylus *c* is so arranged with respect to the recording sheet, that by its own weight or by other means it remains in contact therewith during pauses in operation, and at a distance from the edge thereof which is different from that maintained during the periods of operation.

Figure 3 shows a construction where in the mechanism is located within the cover-like part *B* of the casing, hinged to the base-plate *A* thereof, which serves for the connection of the apparatus with the circuit to be controlled. *a* is the electro-magnet, *d* the armature lever connected to the core piece *h* and pivoted at *g* together with the two-part supporting arm *b* for the stylus *c*; *i* is the clockwork for rotating the recording sheet passing over the support *r* where the stylus *c* rests thereon. The circuit of the electro-magnet *a* comprises a pair of contacts *t*¹ arranged to cooperate with a corresponding pair of contacts *t* on the inside of the base-plate *A* when the cover part *B* is turned over on to the base-plate *A* so

as to connect the said circuit to the line *v* coming from the electrical installation to be controlled and connected to the terminal piece *x* fixed on the inside of the base-plate *A*. The circuit of the electro-magnet *a* still contains a signalling lamp *u* together with a safety fusible *w*, said lamp *u* being arranged to indicate through a window in the casing whether the electro-magnet is energized or not, so as to signalize the operative or inoperative condition of the apparatus.

What I claim is:—

1. Apparatus for recording the rest or operating periods of an electrical installation, comprising a shaft, time-operated means for rotating said shaft, a chart carried by said shaft, a solenoid disposed on its side beneath said chart, a spring-biased arcuate lever attached at one end to the armature of said solenoid and adapted to be moved thereby, the lever extending around said shaft to a position substantially diametrically opposed to said solenoid, a pivot pin on which said lever is mounted, and a stylus consisting of two arms, the first being pivoted to said pin and the second being hinged to the first arm on a pivot pin substantially perpendicular to the first-mentioned pivot pin, so that the point of said stylus swingably overlies the chart.

2. Apparatus for recording the rest or operating periods of an electrical installation, comprising a shaft, time-operated means for rotating said shaft, a chart carried by said shaft, a solenoid disposed on its side beneath said chart, a spring-biased arcuate lever attached at one end to the armature of said solenoid and adapted to be moved thereby, the lever extending around said shaft to a position substantially diametrically opposed to said solenoid, a pivot pin on which said lever is mounted, a stylus consisting of two arms, the first being pivoted to said pin and the second being hinged to the first arm on a pivot pin substantially perpendicular to the first-mentioned pivot pin, so that the point of said stylus swingably overlies the chart and a supporting member underneath the point of the stylus and over which the chart passes.

GUSTAV WINTER.
